UNITED STATES PATENT OFFICE.

OTTO M. MCLIN, OF BOLIVAR, MISSOURI.
RAILWAY ELECTRIC SIGNALING MEANS.

1,260,224.

Specification of Letters Patent. Patented Mar. 19, 1918.

Application filed January 27, 1917. Serial No. 144,975.

To all whom it may concern:

Be it known that I, Otto M. McLIN, a citizen of the United States, residing at Bolivar, in the county of Polk, State of Missouri, have invented certain new and useful Improvements in Railway Electric Signaling Means, of which the following is a full and exact specification.

The present invention relates to railway signaling mechanism, and aims to provide an improved and simplified arrangement and construction of electric signaling devices adapted for automatic operation as a train passes a given point.

More especially the invention comprises an arrangement of electric signaling instruments for the protection of railway crossings and the like, and included within a wayside circuit at such points, the current for energizing said circuit to be supplied from a source of electric energy carried by the passing train.

Further objects of the improvements are to devise a simple and effective mode of automatically closing the circuit through the said source of energy carried by the train as the latter traverses the circuit; and, where a dynamo carried by the train is utilized for supplying the current, the circuit closing means includes provision for maintaining said dynamo operative for only such periods as the train is traversing the signal circuits.

Minor features will appear in the course of the detailed description, which will now be given, reference being had to the accompanying drawing which illustrates one form of construction and arrangement of signaling mechanism that has been devised for embodying the proposed improvements, after which those features of improvement deemed to be novel will be set forth and defined in the appended claims.

In the drawing—

Figure 1 is a perspective view showing the general arrangement and diagram of the path of the electric circuit;

Fig. 2 is a side elevation showing the manner of closing the electric circuit as the train approaches the crossing;

Fig. 3 is a fragmentary plan view of the engine dynamo and connections, and Fig. 4 is a side view of the same; and

Fig. 5 is a detail of a portion of the circuit-closing lever.

The path or conductor 2 for the electric circuit is represented as approaching the crossing 3 from either direction, at which crossing the circuit includes one or more signaling instruments, such as the bells 4 and the lamps 5. At points farthest from the crossing 3 the conductors 2 are suitably insulated; while at the crossing said conductors are electrically connected with the rails of the track 18 to complete the circuit through the latter.

A source of electric energy is provided by the means of a dynamo on the engine as it approaches the crossing, which dynamo may be mounted as at 6 on a suitable shelf 7 just at the rear of the pilot 8 of the engine 9. For driving the dynamo a belt 10 may be arranged to drive from the front axle 11, pulley 12 being mounted on said axle and the belt 10 run from said pulley to a loose pulley 13 on the armature shaft of the dynamo 6. The dynamo circuit is closed through the conductor 2 by means of a swinging circuit-closing lever 15 pivoted at 16 to the shelf 7 and provided with an anti-friction roller 17 for engagement with that portion of the conductor 2 which runs parallel to the track 18, alongside which the said conductor is elevated into the path of said roller 17 as shown in Figs. 2 and 4. The upper end of the lever 15 engages in an opening 19 in one of the arms of the horizontal bell-crank lever 20 which is pivoted to a bracket 21 on the shelf 7. The other arm of the bell-crank lever 20 is provided with a yoke connection to a sliding clutch element 22 which is keyed on the shaft 14 and adapted to be moved into and out of clutch relation with the hub of the pulley 13. The engagement of the roller 17 of the lever 15 with the elevated portion of the conductor 2 swings this lever against the action of a spring 23, and as soon as said lever or its roller 17 becomes disengaged

from said conductor 2, said spring 23 immediately acts to pull the lever 15 in the opposite direction, thereby unclutching the member 22 from the pulley 13 and thus cutting off the drive from the axle 11 the instant the circuit is broken by said disengagement of the roller 17 from the conductor, and allowing the dynamo to come to rest and remain out of operation until the circuit is again closed through said conductor.

It will thus be seen that the engine carries

its own source of electricity for ringing the signal bells or lighting the signal lamps, by the means of the dynamo, and that the circuit through the signaling instruments is automatically closed just as the engine approaches the crossing and the dynamo is started in operation at the same instant; and also that the circuit remains closed and said dynamo remains in operation for energizing the circuit and operating the signaling devices until the engine has reached the opposite side of the crossing, when said circuit is automatically broken and the drive to the dynamo also automatically cut off, so that the dynamo remains idle until the train approaches the next crossing and comes into engagement with the circuit or conductor which guards the same.

While the signal circuit remains broken, the lever 15 is held engaged with a suitable stop 24 projecting from the shelf 7 and serving to limit the movement of said lever under the action of its spring 23.

While the foregoing illustrates one practical form of embodiment of the proposed improvements, the right is reserved to such formal changes or modifications as may fairly fall within the scope of the following claims.

30 Claims:

1. Railway signaling mechanism comprising, in combination, a railway train, a wayside circuit, an electric signaling instrument included in said circuit, a dynamo carried by the train, and means arranged to close said circuit through said dynamo as the train traverses said circuit, said means including provision for automatically stop-

ping the mechanical operation of said dynamo as said train leaves the circuit. 40

2. Railway signaling mechanism comprising, in combination, a railway train, a wayside circuit, an electric signaling instrument included in said circuit, a dynamo carried by the train, and means acting automatically to render said dynamo operative as said train enters the circuit and simultaneously to close the circuit through said dynamo as the train traverses said circuit. 45

3. Railway signaling mechanism comprising, in combination, a railway train, a wayside circuit, an electric signaling device included in said circuit, a dynamo carried by the train, and means arranged to close said circuit through said dynamo as the train traverses said circuit, said means including provision for automatically starting and stopping, respectively, the mechanical operation of said dynamo, as said train enters and leaves the circuit. 50

4. Railway signaling mechanism comprising, in combination, a railway train, a wayside circuit, an electric signaling device included in said circuit, a dynamo carried by the train and actuated by the movement thereof, circuit-closing means operating automatically to close the circuit through said dynamo as the train traverses said circuit, and means actuated simultaneously by the movements of said circuit-closing means for clutching and unclutching, respectively, said dynamo as the train enters and leaves said circuit. 55

In testimony whereof I hereto affix my signature.

OTTO M. McLIN.
